MULTIPURPOSE ELECTRONIC TIMER
Robert L. Burdick, 1405 Dorchester Road, Havertown, Pa.
Filed Nov. 25, 1960, Ser. No. 71,840
3 Claims. (Cl. 307—132)
(Granted under Title 35, U.S. Code (1952), sec. 266)

The invention described herein may be manufactured and used by or for the Government of the United States of America for governmental purposes without the payment of any royalties thereon or therefor.

The present invention relates to a novel and improved multipurpose timing device and more particularly to a novel and improved electronic timing circuit which selectively provides a plurality of timing intervals of a predetermined character.

In studying the physiological and psychological aspects of confinement of the human operator in a sealed cabin or the like in preparation for flight into space, apparatus must often be used which requires the measurement and use of precise intervals of time. Although various types of timing devices for such apparatus have been used in the past, considerable difficulty has been experienced heretofore in obtaining a timing device which is highly accurate and reliable and yet relatively simple and economical in construction.

It is therefore a principal object of the present invention to provide a novel and improved electronic timing device which will accurately and dependably provide any of a plurality of predetermined timed intervals.

It is a further object of the present invention to provide a novel and improved electronic timing device which cannot be improperly triggered by stray voltages.

It is another object of the present invention to provide a novel and improved electronic timing device which is not subject to error due to failure to completely reset the circuit between cycles.

It is a still further object of the present invention to provide a novel and improved electronic timing device which may be readily reset or preset to a predetermined phase of the timing cycle at any time.

Other objects and many of the attendant advantages of this invention will be readily appreciated as the same becomes better understood by reference to the following detailed description when considered in connection with the accompanying drawing wherein:

The drawing is a detailed schematic view of a preferred embodiment of the present invention.

Referring now to the drawing, it will be noted that the energizing circuit for relay R₁ extends from the control signal input line 11 through manual switch S₁ through conductor 13 and through the relay coil to ground. Relay R₁ is also connected for energization to the relay voltage supply line 15 through a circuit that includes conductor 17, the third position of switch S_{2a}, conductor 19, armature 21 of relay R₂ and conductor 23. The energizing circuit for relay R₂ extends from the relay supply line 15 through conductor 25 through the armature of relay R₃ and through the winding of relay R₂ to ground. The energizing circuit for relay R₃ which is also the plate circuit for triode V₁ extends from the positive voltage supply line 27 through the parallel arrangement of relay R₃ and condenser C₁ through resistor 29 through triode V₁ and through resistors 31 and 33 to ground. The control grid of triode V₁ is normally connected to ground through conductor 35, the deenergized armature 37 of relay R₂, conductor 39, and the deenergized armature 41 of relay R₁. When relay R₂ is energized, the grid of triode V₁ is coupled to the voltage supply line 27 through a circuit that includes resistors 43, 45, 47 and 49, conductor 46, the energized armature 37 of relay R₂ and conductor 35. When relay R₁ is

2

energized and relay R₂ is de-energized, the grid of triode V₁ is connected to the parallel arrangement of condenser C₂ and resistor 40 through conductor 35, armature 37 of relay R₂, switch S_{2b} and armature 42 of relay R₁. The charging circuit for condenser C₂ extends from the junction of resistors 55 and 57 through conductor 56, the de-energized armature 42 and condenser C₂ to ground. When switch S_{2b} occupies its second and third positions, the grid of triode V₁ is coupled to condenser C₃ through conductor 35, the de-energized armature 37 of relay R₂, switch S_{2b} and conductor 51. The charging circuit for condenser C₃, which is normally grounded through the de-energized armature 53 of relay R₁, extends from the junction of resistors 55 and 57, through armature 53, switch S_{3a}, the bank of resistors 59, 61 and 63, switch S_{3b} and condenser C₃ to ground. Condenser C₃ may also be instantaneously charged or grounded through manual switch S₄ and conductor 67. The plate circuit of triode V₂ extends from supply line 27 through resistor 43, through the tube and through resistors 31 and 33 to ground. The grid of triode V₂ is coupled to ground both through condenser C₄ and through the de-energized armature 69 of relay R₂. The grid of triode V₂ may also be selectively connected to the ground or the junction of resistors 55 and 57 through switch S₅ and conductor 71. The charging circuit for condenser C₄ extends from the junction of resistors 55 and 57 through conductor 73, switch S_{6a}, the bank of charging resistors 75, 77 and 79, switch S_{6b} and condenser C₄ to ground. Output control line 81 and indicator lamp 83 connected thereto are energized by a circuit that extends from the relay voltage supply line 15 through conductor 23 and energized armature 21 of relay R₂. Relay R₂ also controls energization of output line 85 from either control line 87 or control line 89 as its armature 91 is energized or de-energized.

In operation, switch S₂ occupies its first position when the circuit is to provide an immediate output response for a predetermined interval. Before switch S₁ is closed, the grids of triodes V₁ and V₂ are grounded through the de-energized armatures 37 of relay R₂ and 41 of relay R₁. With grounded grids and cathode potentials slightly above ground due to small current flow through cathode resistors 31 and 33, triodes V₁ and V₂ conduct slightly but relay R₃ in the plate circuit of triode V₁ remains de-energized. When switch S₁ is closed and the timing cycle is initiated, relay R₁ is energized. Energization of relay R₁ opens the circuit to ground for the grid of triode V₁ at armature 41. Simultaneously, energization of relay R₁ couples condenser C₂, which has previously been charged by a circuit from the junction of the voltage divider resistors 55 and 57 through conductor 56 and armature 42 of relay R₁, to the grid of triode V₁. This abrupt increase of potential at the grid of triode V₁ causes an immediate surge of plate current in the plate circuit of triode V₁ and relay R₃ is energized. Energization of relay R₃ causes energization of relay R₂ and output line 81 and lamp 83 are energized through armature 21 of relay R₂. Energization of relay R₂ also opens the normally closed circuit between output lines 85 and 87 and completes a circuit between output lines 85 and 89. When relay R₂ becomes energized and its armature 37 engages its upper contact, the positive potential at the control grid of triode V₁ and the energization of triode V₂ remains substantially cut off. When relay R₂ is energized, the circuit to ground through armature 69 for the grid of triode V₂ and condenser C₄ is opened and condenser C₄ begins to charge through resistor 75, 77 or 79 depending upon the position of switch S₆. After a predetermined charging interval which is controlled by the RC time constant of resistors 75, 77 and 79 and condenser C₄, triode V₂ fires and its plate potential is abruptly

decreased. This abrupt decrease in potential at the plate of triode V_2 is transmitted to the grid of triode V_1 and triode V_1 cuts off. This successively de-energizes relays R_3 and R_2 and output lines 81 and 85 reassume their original condition of energization.

When switch S_2 is moved to its second position, the circuit is conditioned to provide a predetermined output response if the input signal is of sufficient duration. Before the timing interval is initiated by closure of switch S_1 , the grid of triode V_1 is grounded through armatures 37 of relay R_2 and 41 of relay R_1 and the grid of triode V_2 is grounded through the armature 69 of relay R_2 . As described hereinbefore with the grids of triodes V_1 and V_2 grounded, both triodes remain substantially cut off and relays R_3 and R_2 are de-energized. When switch S_1 is closed, relay R_1 is energized. Closure of the upper contacts of armatures 41 and 53 of relay R_1 respectively opens the circuit to ground of the grid of triode V_1 and completes the charging circuit for condenser C_3 . Selection of the proper resistor from the bank of resistors 59, 61 and 63 as well as condenser C_3 determines the interval necessary to charge condenser C_3 to a potential that will fire triode V_1 . If switch S_1 is opened or if the signal on input line 11 is removed before such a potential is accumulated, condenser C_3 is immediately discharged to ground through armature 41 of relay R_1 . When relay R_1 is continuously energized for the required interval, however, a potential is accumulated across condenser C_3 that fires triode V_1 and relay R_3 is energized. This energizes relay R_2 and output lines 81 and 85 and operation of the circuit is identical to that described hereinabove in connection with the timing circuit established when switch S_2 occupies its first position.

When switch S_2 is moved to its third position, the circuit is conditioned to continuously alternate between two conditions of energization, each of which is independently controlled to subsist for a predetermined interval. When switch S_2 engages its third contacts, relay R_1 is immediately energized. This opens the path to ground through armature 41 for the grid circuit of triode V_1 and completes the charging circuit for condenser C_3 through armature 53. After a predetermined charging interval triode V_1 fires and relay R_3 is energized. This energizes triode V_1 and relay R_2 and output lines 81 and 85. Triode V_1 and relays R_3 and R_2 remain energized for the interval required to charge condenser C_4 through resistor 75, 77 or 79, and fire triode V_2 . When this occurs, triode V_1 , relays R_3 and R_2 and output lines 81 and 85 are de-energized for the predetermined interval required to charge condenser C_3 and initiate the entire cycle again.

Switches S_4 and S_5 are provided to selectively ground or fully charge condensers C_3 and C_4 at any time and to immediately establish the phase of the above described timing circuits at a predetermined point in the timing cycle.

Obviously many modifications and variations of the present invention are possible in the light of the above teachings. It is therefore to be understood that within the scope of the appended claims the invention may be practiced otherwise than as specifically described.

What is claimed is:

1. Electronic timing apparatus comprising a pair of electron discharge circuits having a common cathode return; a relay which is coupled to one electron discharge

5 circuit and which is energized when said one electron discharge circuit is energized; means for energizing the relay and producing an immediate response of a predetermined duration when the switch occupies its first position, said immediate response producing means including means for normally maintaining each electron discharge circuit substantially cut off, means for abruptly energizing the one electron discharge circuit and the relay, means responsive to energization of the relay for maintaining energization of the one electron discharge circuit as long as energization of the other electron discharge circuit remains cut off, and means responsive to energization of the relay for maintaining energization of the one electron discharge circuit after a predetermined delay; means for energizing the relay and producing a response of predetermined duration subject to a prescribed condition when the switch occupies its second position, said conditional response producing means including means for normally maintaining each electron discharge circuit substantially cut off, means responsive to the occurrence of an input signal that persists for a predetermined interval for energizing the one electron discharge circuit and the relay, means responsive to energization of the relay for maintaining energization of the one electron discharge circuit as long as energization of the other electron discharge circuit remains cut off, and means responsive to energization of the relay for energizing the other electron discharge circuit after a predetermined delay; and means for continuously energizing and de-energizing the relay for independent predetermined intervals when the switch occupies its third position, said continuous energizing means including a first condenser coupled to the grid of the one electron discharge circuit, a second condenser coupled to the grid of the other electron discharge circuit, means for grounding the second condenser and charging the first condenser when the relay is de-energized, and means for coupling the grid of the one electron discharge circuit to the plate of the other electron discharge circuit and for charging the second condenser when the relay is energized.

2. The apparatus as described in claim 1 further characterized by having means for re-initiating the entire timing cycle and the delay required to energize said other electron discharge circuit.

3. Electron timing apparatus comprising a pair of triode circuits having a common cathode return; means normally maintaining each triode substantially cut off; manually controlled means for energizing one triode circuit after a predetermined interval; a relay which is coupled to said one triode circuit and is energized when said one triode circuit is energized; means responsive to energization of the relay for maintaining energization of the one triode circuit as long as energization of the other triode circuit remains cut off; means responsive to energization of the relay for energizing the other triode circuit after a predetermined delay; and means responsive to energization of the relay for controlling a timed output response.
